UNITED STATES PATENT OFFICE

ROBERT F. HALL, OF SCHENECTADY, NEW YORK

LOCOMOTIVE

Application filed May 12, 1927. Serial No. 190,706.

My invention relates to means for flexibly supporting the "live," or spring supported portion of a locomotive engine, and its object is to so dispose the systems into which the 5 spring appliances are divided, as to more favorably distribute the loads thereon, while preserving the stability of the spring supported portion of the locomotive against lateral rolling movement due to irregularities in the track, centrifugal action on curved track, etc.

A further object of the invention is to provide for the utilization of the improvement on locomotives of the three or four cylinder 15 type, in which space is limited in the portion of the locomotive adjacent to the connections of the inside cylinder or cylinders, by the application of two equalizers between the driving wheels and the leading truck, said 20 equalizers being disposed on each side of the middle longitudinal plane, where the clearance from adjacent parts is most favorable for their location.

The improvement claimed is hereinafter 25 fully set forth.

In the accompanying drawing: Figure 1 is a diagrammatic side view of a locomotive engine, illustrating an application of my invention; Fig. 2, a plan view of the same, with 30 the boiler removed; and, Fig. 3, a plan view of an alternate type of equalizer.

In the practice of my invention, referring descriptively to the specific embodiment thereof which is herein exemplified in a locomotive of the so-called "Mountain" or 4—8—2 type, having a four wheel leading truck, 1, a group of eight driving wheels, 2, and a two wheel trailing truck, 3, the equalizing appliances are divided into two systems. The 35 first or forward system includes the equalizing appliances of the first and second pairs of driving wheels, and the leading truck, these being springs, 4, spring hangers, 5, and side equalizers, 6, and a cross equalizer, 7, the leading truck constituting a central support, and the springs and equalizers, on opposite sides, forming two side supports. The equalizers are spaced at such distance apart that 40 this system is substantially not "cross equal-

ized" for the normal maximum side rolling movements of the spring supported parts.

The second or rear system of equalizing appliances includes those of the third and fourth pairs of driving wheels, and the trailing truck, these being springs, 4^a, spring hangers, 5^a, and equalizers, 6^a; the springs and equalizers on opposite sides forming two side supports. The equalizers, 6^a, of the rear system, may either be connected directly to 55 the driving spring arrangement, as shown, or a cross equalizer may be applied, as in the forward system.

In the ordinary construction, the system above described is applied in substance, but 60 without the relation to a rear system which characterizes my invention. All four pairs of driving wheels are equalized with the trailing truck, with or without a transverse equalizer in rear of the fourth driving axle, 65 and the front ends of the springs over the first pair of driving wheels, are connected by hangers directly to the frame of the locomotive, no equalizer being applied between the driving wheels and the leading truck, nor 70 transversely for connection of the front driving wheel springs. My improvement results in transferring the "dead end" attachments of the driving springs to the frame, to a position near the centre of the driving wheel base, 75 instead of at the front end, as in present practice.

Instead of applying two separate equalizers, as shown in the drawing, they may, without departure from the spirit of my invention, be formed in a single structure, 8, (Fig. 3), having bifurcated end members and a common fulcrum in its body, intermediate 80 said end members, which rest on two points each, of the transverse equalizer and leading 85 truck centre pin, respectively.

It will be noted that, under my invention, with the location of the centre of gravity of the live loads above the spring rigging and equalizer proportions given, the loads on all 90 the springs and on the leading truck, are determinate, as in the present standard construction. The equalization of the front driving wheel system with the leading truck, 95 renders these loads determinate, and the in- 100

troduction of more than two independent equalization systems makes them indeterminate. Two equalizers between the front driving system and the leading truck are provided for the purpose of increasing lateral stability.

I claim as my invention and desire to secure by Letters Patent:

1. In a locomotive, the combination of a frame; a group of driving wheels, journalled therein; a leading truck, swivelling, relatively to said frame; equalizing means on each side of the locomotive, interposed between the driving wheels and the truck, including a transverse equalizer connecting the equalizing means at points forward of the group of drivers and means having connections with said transverse equalizer and truck at points on each side of the longitudinal center of the locomotive adapted to transmit and deliver weight to the truck on opposite sides of its longitudinal middle plane.

2. In a locomotive, the combination of a frame; a group of driving wheels, journalled therein; a leading truck and a trailing truck, each swivelling relatively to said frame; equalizing means, interposed between the driving wheels and the leading truck and adapted to transmit weight from a portion of the group of driving wheels, and deliver it to the leading truck on opposite sides of its longitudinal central planes; and equalizing means, interposed between the driving wheels and the trailing truck, and adapted to transmit weight from another portion of the group of driving wheels, and deliver it to the trailing truck, on opposite sides of its longitudinal middle plane.

3. In a locomotive, the combination of a frame; a group of driving wheels, journalled therein; springs, through which weight is supported on said driving wheels; a leading truck, swivelling relatively to the frame; equalizing means connected to the springs of a pair of driving wheels on each side of the locomotive including a transverse equalizer and hangers connecting the equalizing means to the springs at points forward of the group of drivers and means having connections with said transverse equalizer and truck at points on each side of the longitudinal center of the locomotive for delivering weight supported on the driving wheels, to said truck, on opposite sides of its longitudinal middle plane.

4. In a locomotive, the combination of a frame; a group of driving wheels journalled therein; springs through which weight is supported on said driving wheels; a leading truck and a trailing truck, each swivelling relatively to the frame; spring hangers, connected to said springs; equalizers, connected to spring hangers of the foremost pair of driving wheels, and delivering weight supported by a portion of the group of driving

wheels to the leading truck, on opposite sides of its longitudinal middle plane; and equalizers, connected to spring hangers of the rear pair of driving wheels, and delivering weight supported by a portion of the group of driving wheels to the trailing truck, on opposite sides of its middle longitudinal plane.

5. An equalizer for truck equipped locomotives, having a fulcrum in its body, adapted to be disposed in the longitudinal central plane of the locomotive; and bifurcated end members projecting from said body, having their respective arms forming the bifurcation suitably spaced from each other, to adapt them for engagement at two spaced points on a transverse equalizer member and with a truck on opposite sides of the longitudinal central plane of the locomotive.

6. In a locomotive, the combination of a frame; a truck swiveling relatively to said frame; a group of driving wheels journalled in the frame; equalizing means interposed between the driving wheels and the truck, each side of the locomotive including a transverse equalizer connecting the equalizing means at points forward of the group of drivers and means having connections with said transverse equalizer and truck at points on each side of the longitudinal center of the locomotive adapted to transmit weight from a portion of the group of driving wheels and delivering it to the truck on opposite sides of its longitudinal central plane; and equalizing means independent of said first equalizing means for another portion of the group of drivers.

7. A locomotive equalizer, comprising a fulcrum; a pair of members beyond the fulcrum at one end of the equalizer, suitably spaced from each other to adapt each for operable engagement with equalizing means of the locomotive for the transmission of weight; and means beyond the fulcrum, at the opposite end of the equalizer, adapted for operable engagement with resilient means of the locomotive for the transmission of weight.

8. A locomotive equalizer, comprising a fulcrum; bifurcated means beyond the fulcrum, at one end of the equalizer, the members forming the bifurcated means, being suitably spaced from each other, to adapt each member for operable engagement with equalizing means of the locomotive, for the transmission of weight; and bifurcated means beyond the fulcrum, at the opposite end of the equalizer, adapted for operable engagement at two points, with resilient means of the locomotive, for the transmission of weight.
